International Search Report and Written Opinion dated Jan. 13, 2020 for International Patent Application No. PCT/US2019/042194, 16 pages.

Primary Examiner — Samantha Q Lawrence*(74) Attorney, Agent, or Firm* — Morgan, Lewis & Bockius LLP(57) **CLAIM**

The ornamental design for a bollard, as shown and described.

DESCRIPTION

FIG. 1 is a front, top perspective view of a bollard showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines shown in FIGS. 1-7 illustrate portions of the bollard that form no part of the claimed design.
